UNITED STATES PATENT OFFICE.

CLARENCE W. PIPER, OF ST. PAUL, MINNESOTA, ASSIGNOR TO ADOLPH C. WILCKEN, OF ST. PAUL, MINNESOTA.

BED-SPRING FABRIC.

1,335,984.

Specification of Letters Patent.

Patented Apr. 6, 1920.

Application filed April 6, 1917. Serial No. 160,214.

To all whom it may concern:

Be it known that I, CLARENCE W. PIPER, a citizen of the United States, residing at St. Paul, in the county of Ramsey and State 5 of Minnesota, have invented a new and useful Improvement in Bed-Spring Fabrics, of which the following is a specification.

This invention relates to certain new and useful improvements in borders for bed 10 springs and the provision of a novel form of wire fabric, the primary object being to provide an improved form of bed bottom which is light and durable, of economical construction and very neat in appearance.

15 Other and further objects and advantages of the invention will be hereinafter set forth and the novel features thereof defined by the appended claim.

In the drawing,

20 Figure 1 is a detail plan view of a bed bottom constructed in accordance with my invention; Fig. 2 is a side view broken away; Fig. 3 is a sectional detail of one means of connecting the fabric to the mattress frame; Fig. 4 is a detail showing the manner of constructing the fabric; Figs. 5 and 6 are different forms of the clip spacing means employed; and Figs. 7 and 8 show modified arrangements of the border with 25 respect to the fabric.

Like numerals of reference refer to like parts in the several figures of the drawing.

Referring to the drawing 2 represents the side bars, and 3 and 4 the foot and head bars, respectively, of a mattress frame which, it will be understood, may be of any 35 preferred size, shape and configuration, though as shown, these parts are of angle iron secured at their points of intersection by means of bolts or rivets 5.

At each of its longitudinal edges, the improved wire fabric employed is provided with a border consisting of a pair of spaced built-up wires, each of which is bent intermediate its length to form strands 6 and 7 40 in parallel proximity to one another and has its ends rigidly fastened together by means of a clamp 8 to be hereinafter more specifically referred to. Each of the pairs of strands thus formed is secured at intervals to its adjacent pair through the medium of a plurality of clips consisting of wires 9 of suitable length, each of the ends of which is caused to encircle and tightly clamp a pair 45 of the strands as clearly shown in Fig. 5.

and in this way retain the individual pairs of strands distanced apart. More particularly, the wire 9 forming the clip is bent at points removed, the ends thereof to form shoulders 9' against which the fabric 60 strands abut and is thence continued around the strand so that the ends of the wire rest against the shoulder as shown. By this construction of clip, it has been found that there is less tendency of the strands being 65 unintentionally forced out of the loop formed by the encircling part of the wire.

In Fig. 4 is shown a detail of the manner in which the strands 6 and 7 of my improved border are constructed. As illustrated, these 70 strands consist of a wire 10 of suitable size and continuous length forming a core about which is tightly and spirally wound or wrapped a plurality of small flexible wires 11 whereby a finished construction is formed 75 that is exceedingly durable and which at the same time presents a neat appearance and is light in weight.

As above pointed out, a continuous wire of this type is bent midway of its length to 80 form the strands 6 and 7, a helical spring 12 being utilized for securing the looped end 13 of the wire to the head bar 4 of the frame. At the other extremity, the ends of the wire are secured rigidly together by means of the 85 clamping device 8, which is double crimped as shown at 8', the holding effect of which is augmented by the employment of the somewhat yieldable surfacing formed by the spirally wrapped wires 11. A coil spring 90 15 is secured at one end to the foot bar 3 and is provided at its other end with a hook 16 which is passed between the strands 6 and 7, as shown in Fig. 3 to properly secure the strands within the mattress frame. As further shown in this figure, the clamped ends 95 of the wire are disposed inside the spring 15 so as to obviate any possibility of bed clothing engaging being damaged by contact therewith.

The space intermediate the border edges may be occupied by fabric of any suitable construction, but as shown it consists of continuous wires each bent midway of its ends to form parallel strands 17 and 18 spaced 105 apart by clips 19, see Fig. 6, very similar in construction to the clip 9 shown in Fig. 5. It will be noted that these clips 19 not only space the strands of each pair apart, but they are also used in alternate arrange- 110

ment to secure the adjacent strands of different pairs together. It will also be noted that the borders, though positioned in proximity to the strand of the next adjacent pair, 5 are not connected by means of clips or otherwise to such strand as it has been found in practice to be unnecessary due to the lateral rigidity of the borders formed in the manner heretofore described.

10 In Fig. 7 is shown a modified construction of fabric wherein the strand 18 of the outermost portion of the fabric overlies to some extent the adjacent strand 7 of the border and in this way tendency of the mattress or 15 bed clothing to work its way between the border and the fabric is eliminated. Furthermore when excessive pressure is brought to bear upon the border, it will be understood that a degree of lateral movement 20 thereof is permitted without interfering with the substantial continuity of the bed bottom.

In Fig. 8 the border is shown as constructed of a single pair of strands 6 and 7 25 spaced at intervals by means of clips similar to those 19, the ends of which are bent upwardly around the strands of the border; while the strands 17 and 18 of the fabric are 30 spaced by means of clips substantially identical in all respects with those 19 except that their ends are bent downwardly around the strands. By this means, the strand 18 of

the outermost portion of the fabric is adapted to overlie and in effect nest between the strands 6 and 7 of the adjacent border.

35 In neither the preferred form nor the modifications shown, is the fabric attached or in any wise secured to the border as in this manner a greater give or yield is obtained without sacrificing the comfort of the 40 user.

In accordance with the patent statutes, I have described the principles of operation of my invention, together with the apparatus which I now consider to represent the best 45 embodiment thereof, but I desire to have it understood that the construction shown is only illustrative, and that the invention can be carried out by other means and applied to uses other than those above set forth 50 within the scope of the following claim.

Having described my invention, what I claim as new and desire to protect by Letters Patent is:—

A bed bottom comprising a fabric having 55 a border on each side thereof formed of wire strands which are spaced apart, a side edge of said fabric overlying the adjacent portion of said border to prevent bed clothes working under the border.

60 In testimony whereof I have signed my name to this specification.

CLARENCE W. PIPER.
